UNITED STATES PATENT OFFICE.

WARD G. CALLENDER, OF MANSFIELD, OHIO.

SHOE-CLEANER.

1,245,869.

Specification of Letters Patent. Patented Nov. 6, 1917.

Application filed April 19, 1916. Serial No. 92,085.

To all whom it may concern:

Be it known that I, WARD G. CALLENDER, a citizen of the United States, residing at Mansfield, in the county of Richland and State of Ohio, have invented certain new and useful Improvements in Shoe-Cleaners, of which the following is a specification.

My invention relates to improvements in shoe-cleaners, and one object of my invention is the provision of an article for this purpose which can be fixed stationary or rigid, or which may be portable to permit the cleaner to be used by hand and easily carried in the trunk or suit case.

Another object of my invention is the production of a rigid or portable device which will quickly and thoroughly clean the sole of the shoe and at the same time brush and polish the shoe with ease and efficiency.

Another object of my invention is the provision of a shoe cleaner which will be small and compact in size to occupy a small space; which will be easy to use and thoroughly efficient; which will cost little to manufacture and which will be practical.

To attain the objects stated and such others as pertain to an invention of this character, my invention consists of a shoe cleaner embodying novel features of construction and combination of parts, substantially as disclosed herein.

Figure 1 is a perspective view of a hand or portable shoe cleaner constructed in accordance with and embodying my invention.

Fig. 2 is a detail view showing the manner of mounting the cleaner or scraper and the brushes, and Fig. 3 is a perspective view of the device with the brushes removed.

Fig. 4 is a side view of a complete shoe cleaner of modified construction, and

Fig. 5 is a sectional view of this form of my improvement.

Fig. 6 is a detail view of another modified construction of the device.

Referring by numeral to the drawings, in which similar numerals of reference denote the same parts in all the views:—

The numeral 1, designates an open frame of bail or yoke shaped form, having a base or supporting portion 2, and a handle or grasping portion 3, for manipulating the cleaner.

This frame is of the proper length to suit the purpose, of a size to be carried in the trunk or suit case, and of metal of the proper thickness, and in forms 1, 2, and 3 of my

device to the base 2, is pivoted at 4, the hand lever 5, which is adapted to contact with the edges of the sole of the shoe to cut the dirt or accumulation therefrom, while to the sides of the frame are secured in openings 6, the reduced ends 7, of the sole scraping or cleaner plate 8, the recesses 9, of said plate forming seats for the brush heads 10, having the brushes 11, said heads being rigidly secured to the sides of the frame by screws or desired fastenings 12.

In the construction of my device shown in Figs. 4 and 5, to the base 2, of the frame is secured the member 13, carrying the horizontal scraping plate 14, and the vertical brushes 15, for cleaning the sole of the shoe and brushing the sides, while to the brushes 15, are secured the brushing and polishing pads 16, for acting on the top or surface 75 of the shoe upper.

In the construction shown in Fig. 6, the scraper plate 17, is supported above the base of the device and secured to the frame at 18, while the seats 19, are provided and the support has its vertical arms bifurcated or forked at 20, to fit the grooves 21, in the brush heads and permit them to fit in the forks 20, and rest in the seats 19, and to permit their ready application and removal 85 when found necessary or desirable.

The manner of using my device is so obviously apparent that a lengthy explanation is not deemed necessary, the sole of the shoe being cleaned by the lever and scraper plate 90 and the entire upper being brushed by the brushes and pads, effecting a rapid and thorough cleaning of the shoe with ease.

The device may be used as a stationary or hand article; may be conveniently packed 95 and carried; is of attractive appearance, and its simplicity, durability and cheapness insure a practical article of this character.

In Fig. 1 the frame 1, of my cleaner is provided with a hinged connection 1', which permits the device to be folded to cause it to occupy a small amount of space in order that it may be easily carried in a trunk or suit case. In fact the cleaner may be made in connected sections which will permit of the article being folded to occupy a small space.

I claim:—

1. The shoe cleaner herein shown and described, consisting of a vertically disposed frame, the horizontally arranged scraper mounted in said frame, vertically arranged

brushes carried by the frame and arranged contiguous to said scraper, and a hand operated sole scraping lever carried by the frame in proper relation to the scraper and brushes.

2. A shoe cleaner consisting of a yoke shaped frame, a scraper plate mounted horizontally in the lower portion of said frame and having a recess in each end on its upper 10 edge, brush heads secured to the frame and

fitting in said recesses, and brushes carried by the heads and operating to clean the shoe upper.

In testimony whereof I affix my signature in the presence of two witnesses.

WARD G. CALLENDER.
